W. C. HORNER

HINGE

Filed Feb. 23 1927

INVENTOR.
William C. Horner
BY
George H. Horner
ATTORNEY.

UNITED STATES PATENT OFFICE.

WILLIAM C. HORNER, OF CINCINNATI, OHIO.

HINGE.

Application filed February 23, 1927. Serial No. 170,221.

My invention relates to hinges for use in furniture, cabinet work and buildings.

My primary object is to provide a hinge structure which is adapted for insertion into kerfs in the two pieces to be hinged and cemented in place. Such a hinge avoids the necessity of chiseling out countersinks in the pieces to be joined, which is normally hand work, and avoids the use of screws for securing the hinges in place. It provides a hinge which can be made of fairly light materials, such as for example, from sheet metal stampings. The hinges may be made to permit the hinged objects to swing 15 through 180 degree angles with relation to each other, and be much more concealed, than the ordinary flush hinge, in which the entire pintle portion must project from the meeting line of the hinged objects. The 20 hinges, when set into kerfs in the hinged object, have their plate portions, which often are unsightly, completely concealed.

In a preferred form I make my hinge of sheet metal plates which are arranged to 25 engage over wooden filler strips. The kerfs can readily be formed in the objects to be joined in a miter sawing machine, and with great accuracy. The hinges with the filler strips in place can be dropped into the kerfs, 30 together with a suitable glue or cement and will remain permanently in place.

I have selected for illustration, two forms of my hinge, which show a number of advantages, which I will point out, and the 35 novelty inherent in my invention will be pointed out in the appended claims.

In the drawings:

Fig. 1 is a cross section through a double hinge showing my invention.

Fig. 2 is a perspective of one of the link sections of the double hinge.

Fig. 3 is a perspective of one of the hinge leaf sections of the double hinge.

Fig. 4 is a perspective of a part of one of 45 the double hinges.

Fig. 5 is a perspective of a wooden filler strip for the hinge of Fig. 4.

Fig. 6 is a perspective illustrating a piece of wood kerfed for the reception of my 50 hinge.

Fig. 7 is a perspective detail showing a portion of two hinged sections.

Fig. 8 is a perspective showing two pieces joined by a single hinge.

Fig. 9 is a perspective of a portion of the 55 single hinge.

In the illustrated embodiments of my invention, the hinge leaves are stamped out of sheet metal and suitably formed in a few simple die operations. I have illustrated 60 but one form of hinge leaf, namely a piece having a main body 1, a flange 2, for engaging the wood filler strip, and a rolled portion 3 for the hinge pintle. These pieces can be stamped from sheet metal without waste, 65 being rectangular, and can have any finish desired.

In the double hinge the link is formed with a flat body portion 4, with two rolled portions 5, 5, for the two-hinge pintle. 70

In assembling the hinge, when it is the double hinge, the two pintles 6, 6, are thrust through the links, then through two hinge leaves, one on each pintle, then through another link, and so on, thus building up a 75 hinge of whatever length is desired, with the only requirement of using standard pieces and cutting the pintle to the desired length.

The filler strips for the hinges may be 80 made up cheaply and effectively from wood or other fibrous material, which is preferable to metal for use with the usual veneer glue, employed by cabinet makers. Metal can be used for the filler strip, or the filler 85 strip omitted, and a cement of good body used. As illustrated the strips are formed having a body 7, with ridges 8, interspaced for flush reception between them of the hinge leaves. The edges of the strips are 90 also ridged, or cut in, to form countersinks 9 for the flanges of the hinge leaves.

To illustrate the mode of setting the hinge in place, I have shown two pieces of wood 95 10 and 11, which are each kerfed inwardly from the outer meeting edge as with the kerfs 12 and 13. The kerfs fit the hinges with the filler strips in place, and the hinges are smeared with glue and set into the kerfs where they will remain.

As compared to the task of countersinking the meeting faces of the wood, setting the hinges, drilling the holes for the screws, and finally screwing the hinges down, this operation is quite simple and the finished article 100 more permanent.

The hinge leaf sections are keyed in place by the wood filler strip and the filler strip 105

and leaves are solidly glued into the kerfs, resulting in very slight weakening of the wood. The strain on such a hinge is not localized, as is often the case on a single screw, in the usual flush set hinge, but is distributed through the kerf.

In the double hinge, the parts may be swung a full 180 degrees on each other, due to the links swinging around on the pintles, 10 and spacing the corners of the hinged pieces away from each other, sufficient to permit the swinging. Also there will be no radially projecting hinge part, when the pieces are swung around to position of laying 15 against each other, because no projection of the rolled portions of the leaves, is required.

This one advantage is not present so much in the single hinge, although the pintles may 20 be made of much less size, than in the usual type of hinge. I have shown the leaves 1; with a single pintle 14 passing through them in Fig. 9. This hinge may be provided with a wood filler strip 15, suitably countersunk, 25 to receive the alternate leaves. It may be set into like kerfs in the wooden pieces 16, 17 as shown in Fig. 8.

The two illustrated embodiments of my invention are merely two of a great many possible forms. The kerfs can be cut at any 30 angle to suit the type of finish or molding on the hinged parts. When the wood filler strips are not employed, a fibrous substance can be mixed with the glue, making a mastic 35 in the kerfs.

In its general aspects, my invention is a new method for hinging one part to another—using for such articulation a hinge devised so that it be imbedded in the parts 40 connected in such a manner that only the knuckle with the pin that attaches them is exposed to view at any time.

Having thus described my invention, what I claim as new and desire to cover by Letters Patent, is:—

1. In a hinged structure, two parts to be hinged together having kerfs in the meeting faces of said parts, a hinge formed of two series of hinge plates, pintle means for said hinge co-operating with said plates, 50 filler strips of suitable material engaging each one of the series of plates, and said plates and filler strips cemented in place in said kerfs.

2. A hinge, for the purpose described, 55 comprising two series of hinge leaves formed of sheet metal, and having rolled portions for a pintle, pintle means, and filler strips for said leaves, said strips having countersunk portions therein, into which said leaves 60 are set, said filler pieces formed of wood so as to make a good cement bond in kerfs in pieces of wood to be hinged.

3. A hinge for the purpose described, comprising two series of hinge leaves formed of sheet metal and having rolled portions for a pintle, and terminal flanges, pintle means therefor, and filler pieces countersunk to receive the bodies of said hinge leaves and the terminal flanges, said filler pieces formed of wood so as to make a good cement bond 70 in kerfs in pieces of wood to be hinged.

4. In a hinged structure, two parts to be hinged together having kerfs therein into which the hinge elements are to be set, and a hinge formed of metal plates having pintle retaining means, a pintle therefor, said metal plates cemented in place in said kerfs with the pintle retaining means only exposed, and filler pieces secured to said metal 75 plates and cemented into the kerfs with the plates.

WILLIAM C. HORNER.
